TROLLEY-POLE CONTROLLER FOR ELECTRIC CARS.

1,206,758.

Specification of Letters Patent.

Patented Nov. 28, 1916.

Application filed March 6, 1916. Serial No. 82,364.

To all whom it may concern:

Be it known that I, CLARENCE V. GREENAMYER, a citizen of the United States, residing at the city of Los Angeles, in the county of Los Angeles and State of California, have invented new and useful Improvements in Trolley-Pole Controllers for Electric Cars, of which the following is a specification.

10 My invention relates to means for controlling by air pressure the position of the trolley pole on an electric car driven by current supplied by an overhead feed wire and the object thereof is to provide a simple and 15 efficient device operated by air pressure alone that will maintain the trolley wheel in contact with the feed wire and will lower the trolley wheel below the span wires when the wheel accidentally leaves the feed wire 20 while running.

A further object is to provide a lock that will prevent the pole from turning when the wheel leaves the wire.

In the drawings forming a part of this 25 application: Figure 1 is a side elevation partly in section of the base of a controller of preferred construction equipped with my improvements. Fig. 2 is a top plan partly in section of the parts shown in Fig. 1, the 30 car roof being omitted. Fig. 3 is an enlarged sectional detail of the front end of the cylinder and the air piston and parts connected thereto. Fig. 4 is a central longitudinal section of a modified form of controller. Fig. 5 is an enlarged sectional detail of the rear end of the air cylinder and parts connected thereto.

In the drawings 10 is the spindle or trolley base plate which is secured upon the top 40 11 of the car. A base swivel 12 provided with upwardly and rearwardly projecting arms 13 and 14 is pivotally connected by the hollow swivel pin 15 with the base plate 10. Pin 15 is connected by pipe 16 with the compressed air reservoir 16^a, shown diagrammatically, which furnishes air to operate the brakes. The construction and connection of parts thus far described are substantially like those described in U. S. Letters Patent 782,195. An air cylinder 17 is pivotally mounted in the outer ends of arms 13 and 14 by hollow bolts 18 and 19. These bolts pass through arms 13 and 14 in screwthreaded engagement and are smooth 50 where they pass into bosses 20 on the sides of the cylinder 17. Bolt 18 is connected by pipe 20^a to pin 15. Extending from the inner end of bolt 18 is a channel 21 in the walls of cylinder 17 which opens into the front end of the cylinder. Within cylinder 60 17 is a piston 22 which is connected to stem 23 by bolt 24. Stem 23 is pivotally connected to arm 25 secured upon the trolley pole base socket 26 in which socket is mounted the trolley pole 27. Socket 26 is 65 bifurcated and is pivotally secured to swivel base 12 by bolt 28. The furcated arms 29 of socket 26 project downwardly and rearwardly of bolt 28 and are connected by side rods 30 with yoke 31. Rigidly connected 70 to swivel base 12 is rod 32 on which rod is mounted balancing spring 33. This spring balances the weight of the trolley pole. The outer end or head 35 of bolt 24 tapers inwardly forming a valve seat and is provided 75 with a number of transverse channels 36. These transverse channels are connected by a longitudinal channel 37 with a transverse channel 38 near the rear end which extends from channel 37 and connects it with channel 39 in the follower ring of the piston. The hole in the follower ring is larger than bolt 24 to form an air chamber around the bolt so that air can reach channel 38 if channel 39 is out of register. Slidably mounted 80 upon the outer end of bolt 24 is valve 40 which normally is held seated by spring 41 to close channels 36. Valve 40 and its seat are preferably on a ten degree angle and are ground. A diaphragm 42 is secured to 85 valve 40 and to piston 22. Piston 22 is recessed at 43 to chamber the inner end of valve 40 and spring 41 when the valve is unseated as hereafter explained. The inner end of this recess is connected by channel 90 44 in bolt 24 with atmosphere in the hollow piston stem. Extending from the inner end of bolt 19 is a channel 45 in the walls of cylinder 17 which opens into the rear end of the cylinder. The channel in bolt 19 is 95 connected by pipe 46 with piston chamber 47 mounted on the side of the swivel base. In this chamber is a piston 48 which carries a locking bolt 49 that projects downwardly through the bottom of the chamber. Around 100 this locking bolt is coiled spring 50 which normally holds piston 48 in the upper end of chamber 47 and prevents bolt 49 from engaging any of the notches 51 in the base plate 10. There are preferably two of these 110

notches, one at each side of the bolt 49. A relief valve 72 is mounted in the outer end of cylinder 17 as specified in Patent 782,195 for the purposes specified in said patent.

5 In the operation of my controller the air is turned into the inner end of cylinder 17 thereby forcing the piston toward the outer end and causing the free end of the trolley pole to rise and carry the trolley wheel 10 into engagement with the feed wire. Now, should the trolley wheel accidentally leave the feed wire when the car is running the piston in cylinder 17 moves quickly toward the outer end thereof. This quick movement 15 causes the relief valve to close and the air is trapped in the outer end of the cylinder thereby bringing a pressure upon diaphragm 42 which then moves toward the piston, carrying with it valve 40. The air in the front 20 end of the cylinder then rushes through channels 39, 38, 37 and 36 into the outer end of cylinder 17 and puts the same air pressure on the outer face of piston 22 as there is on the inner face of the piston. As only a small 25 portion of the inner face of the piston is subject to air pressure and the whole of the outer face is then subject to air pressure the piston is quickly driven back to the front end of cylinder 17 thereby bringing the free 30 end of the trolley pole below the span wires where it is held until the air pressure is released by emptying cylinder 17 of its compressed air. When the compressed air pressure is released in the cylinder spring 41 returns 35 valve 40 to its seat and when the compressed air is again turned on valve 40 prevents the compressed air from reaching the outer end of cylinder 17. In the first entry of compressed air into the outer end of cylinder 17 40 a portion thereof will pass into chamber 47 and force piston 48 to carry bolt 49 into a notch 51 thereby preventing the trolley from rotating on its base plate. The releasing of compressed air pressure in cylinder 17 also 45 releases the pressure in chamber 47.

In the modified form shown in Figs. 4 and 5 the air is led into the air cylinder 17 in the same manner. Piston 52 has no opening therethrough. In the outer head 53 of cylinder 17 is an opening or port 53^a in which is screwed a hollow nut 54 which is held positioned by a lock nut 55. A hollow casing 56 is connected by pin 57 to the outer head 53, of cylinder 17. A pipe 59 connects casing 56 with the front end of the cylinder 17. A tubular stem 60 having a tapered head 61 passes through nut 54 and screws into casing 56. Head 61 tapers rearwardly preferably on a ten degree angle and has a number of 55 transverse channels 62 passing therethrough. These channels open at the center into a longitudinal channel 63 in stem 60, which 60 channel opens into casing 56. A valve 64 is slidably mounted on stem 60 and is normally held by spring 65 to close channels 62. A

diaphragm 66 is connected to valve 64 and to head 53. A gasket 67 makes a tight joint between the rear head and the body of cylinder 17. Bolts 69 hold the head positioned on the body. A channel 70 through the head 70 connects the space between the diaphragm and the head with atmosphere. A relief valve 71 permits air to flow into and out of cylinder 17 under working conditions. A base lock of the same kind as in the preferred form is provided. In this form when the trolley wheel accidentally leaves the feed wire when the car is running the piston suddenly and quickly moves toward the rear end of the cylinder 17. The initial movement 75 closes the relief valve, sets the lock as in the preferred form and drives valve 64 to unclose channels 62. The air then rushes from the front end into the rear end of cylinder 17. As piston 52 has its whole area on the 80 rear side subject to the compressed air pressure and but a small ring on the other side subject to compressed air pressure the free end of the trolley pole is quickly brought below the span wires and held there until the 85 air pressure is released.

Having described my invention what I claim is:

1. In a trolley pole controller the combination of a trolley pole; a compressed air reservoir; with an air cylinder having a piston operatively connected with the trolley pole, said cylinder being in communication with said reservoir at the front only of said cylinder and having its rear end closed; a 95 passage way connecting the ends of the cylinder; a valve on said passage way normally closing the same; and means to open the valve on the passage way between the front and rear ends of the air cylinder when the 100 trolley wheel accidentally leaves the feed wire.

2. In a trolley pole controller the combination of a compressed air reservoir; an air cylinder pivotally connected to a support; a 110 piston in said air cylinder; a channel connecting said air cylinder at the front end thereof with said reservoir; a trolley pole pivotally connected to said air cylinder support; a stem connected to the front side of 115 said piston and pivotally connected to said trolley pole; means carried by said piston to open communication through the piston between the two ends of the air cylinder when the trolley wheel accidentally leaves the feed 120 wire when the car is running.

3. In a trolley pole controller the combination of a compressed air reservoir; an air cylinder pivotally connected to a support; a piston in said air cylinder; a channel connecting said air cylinder at the front end thereof with said reservoir; a trolley pole pivotally connected to said air cylinder support; a stem connected to the front side of 125 said piston and pivotally connected to said 130

trolley pole, said piston having a follower ring provided with a transverse channel; a bolt having a tapered head connecting said piston and stem, said bolt having transverse 5 channels in the head and a transverse channel within the follower ring of the piston from the center to one side a longitudinal central channel connecting the transverse channels, and a valve slidably mounted 10 on said bolt and normally closing the transverse channels in the head; a spring

to normally hold said valve positioned; a diaphragm secured to said valve and to the piston, said piston having a channel therein opening at one end to at 15 inosphere and at the other end to the space between the piston and diaphragm said last named channel being in the bolt connecting the piston to its stem.

In witness that I claim the foregoing I 20 have hereunto subscribed my name.

CLARENCE V. GREENAMYER.
